WALL LAMP

Leonard Atkin, Springfield, N.J., assignor to Stone Manufacturing Co., a corporation of New Jersey

Filed Nov. 3, 1960, Ser. No. 62,725

Term of patent 14 years

(Cl. D48—4)

FIGURE 1 is a top plan view of a wall lamp showing my new design;

FIGURE 2 is a front elevational view thereof;

FIGURE 3 is a rear elevational view thereof; and

FIGURE 4 is a side elevational view thereof.

FIGURE 5 is a reduced perspective view as seen from the bottom and one side thereof.

The parallel lines shown on the lower portion of the lamp in FIGS. 2 and 5 indicate surface ornamentation in the form of striations.

I claim:

The ornamental design for a wall lamp, substantially as shown and described.
